BOAT CONTROL MECHANISM

Ernest A. Clark, Jr., Fullerton, Calif.

Application June 21, 1946, Serial No. 678,459

7 Claims. (Cl. 115—35)

1

This invention relates to controls for the propelling mechanism of relatively small power boats, and particularly to apparatus for controlling the operation of one or two internal combustion engines employed to rotate the boat-propelling mechanism.

Prior-known apparatuses of the above-referred-to type usually employ separate reversing-gear and throttle-control levers so that when dual motors are to be controlled, four separate, independent levers are required simultaneously to be actuated in addition to the operation of the steering mechanism. Prior-known devices that combine the throttle-control and the reversing-gear levers in a unitary assembly are objectionable because they usually rely for operation on electrical equipment which is best avoided in critical points in all small boat constructions. Other such devices include complicated cam structures requiring expensive designs that easily get out of order and are difficult to repair. Still others are of awkward constructions not adaptable to dual motor control.

Objects of this invention include the provision of a control for a relatively small power boat wherein a simple mechanical lever system is employed to effectively actuate the reversing gear of the power boat; the provision of such a control in which the actual reversing-gear actuation is effected through the functioning of a servomotor mechanism; the provision of such a control in which a single lever is provided for both reversing-gear and throttle operation; the provision of such a control for dual motors wherein the reversing-gear and throttle operation of each motor is controlled by a single, separate lever so arranged that both can simultaneously be operated by a single operator; the provision of such a control for dual motors that can be operated to maneuver the boat independently of the steering mechanism; and the provision of such a control in which it is impossible to operate the throttle while the reversing gear is being actuated.

The above, as well as other objects and novel features of the boat control, will become apparent from the following specification and accompanying drawings, in which:

Figure 1 is a perspective view of dual motors for a power boat to which the principles of the invention have been applied;

Figure 2 is a modification of a portion of the structure shown in Figure 1;

Figure 3 is a section taken substantially along line 3—3 of Figures 1 and 2;

2

Figure 4 is a detail of assembly showing an interlocking structure to prevent operation of the throttle of the motor when the reversing gear is being actuated;

5 Figure 5 is a section taken substantially along line 5—5 of Figure 1; and,

Figure 6 is a schematic diagram of a portion of the control including one of the servo-motors for operating one of the reversing gears.

10 Referring to Figure 1, the invention is shown as applied to a relatively small power boat including a port motor P and a starboard motor S, both of identical design and construction. Motors P and S are provided with identical reversing-gear mechanisms R (only one of which is specifically shown, Fig. 6) that are adapted to be operated through the actuation of servomotors S'. The servo-motors S' which supply the power for operating the reversing-gear mechanisms R are controlled by the operation of identical manual controls M. Conventional carburetors on motors P and S are also controlled by the manual controls M.

25 Referring to Figure 6, the mechanism R is of any well-known design, and it will become evident from the description which follows that the type of such reversing mechanism in no way limits the application of the principles of the invention. It includes an oscillatable shaft 10 to which an operating handle 11 is fixed. A sleeve 12 is splined to a driven or propelling shaft 13, and includes a clutch throw-out bearing 14 having a non-rotatable race 15, a rotatable race 15' integral with the sleeve 12, and anti-friction balls 30 between the races. Trunnions 16 on the race 15 are engaged by a fork 17 that is fixed to shaft 10. Accordingly, oscillation of the handle 11 causes reciprocation of sleeve 12. Sleeve 12 is also provided with three peripherally-arranged sockets 18 into each of which the one end of a bell-crank lever 19 extends. The opposite arms of bell-crank levers 19 are adapted to engage means for moving a plurality of normally-stationary clutch discs axially into engagement with other normally-rotating clutch discs. A locking bar 20 is attached to handle 11 and it cooperates with a brake band 21 for preventing the rotation of a housing 22 of the mechanism R. The construction and arrangement of the parts are such that movement of handle 11 in one direction (Fig. 6) causes the movement of the normally-stationary clutch discs into engagement with normally-rotating discs, and releasing of brake band 21 to permit housing 22, bell-cranks 19 and sleeve 12

35 to rotate as a unit, thereby driving the propelling

shaft in a forward direction. Movement of handle 11 in the opposite direction separates the clutch discs and tightens the brake band 21 to stop the rotation of housing 22, thereby causing the propelling shaft 13 to be driven in a reverse direction through a train of reversing gears within housing 22.

The handle 11 is adapted to be oscillated by a servo-motor S' comprising a cylinder 23 within which a piston 24 is adapted to be reciprocated. The piston 24 is integral with a partially hollow tube 25 that is connected to the handle 11. A valve 26 extends into the hollow tube 25 and includes adjustable nuts 27 and 27' for limiting its longitudinal movement therein.

The engine P is adapted to drive a fluid pump 28, the pressure fluid from which passes through a line 29 into an accumulator 30, thence through a safety relief valve 31 that is connected to a reservoir 32 by a line 33. The pressure fluid passes through line 34 to the cylinder 23. With the parts in the neutral position shown in Figure 6, the pressure fluid passes through a port 35 in the piston 24 to the interior of tubular member 25, between two spools 36 and 37 on the valve rod 26. The pressure fluid then passes through the two inclined ports 38 and 39 in the piston 24 to opposite sides thereof, holding the piston against movement, and consequently the handle 11 also.

The cylinder 23 is provided with exhaust ports 40, 41 located, respectively, adjacent to the left and right hand ends of two spools 42, 43 formed on the valve 26. In the position shown in Figure 6, the fluid acting on each face of the piston 24 exhausts through ports 40 and 41 into chambers formed by spools 37, 42 on the one hand, and spool 43 and a shoulder 44 on valve 26 on the other hand. The valve-rod 26 is provided with a drilled longitudinal passage 45 and three transverse ports 46, 47 and 48 extending through the valve-rod and intersecting passage 45.

The exhaust from ports 40, 41 passes through ports 46 and 47, thence through drilled passage 45, thence through port 48 to an exhaust line 49 leading to the intake side of pump 28. This side of pump 28 is also connected to the reservoir 32 by a line 50. From the foregoing, it is evident that with the parts in the position shown in Figure 6, the piston 24 is held against movement by equal fluid pressure on each side thereof, while still permitting free, continuous flow of fluid through the system, thereby preventing overloading of pump 28. The position of the parts as shown in Figure 6 represents the neutral position of the reversing mechanism R and a spring-pressed detent 26' is adapted to cooperate with a recess in shaft 26 to inform the operator when the apparatus is in a neutral position.

Movement of valve 26 rightwardly causes exhaust port 41 to be closed by spool 43, while exhaust port 40 remains open to port 46. Accordingly, piston 24 moves rightwardly an amount proportional to the rightward movement of valve 26 until exhaust port 41 passes beyond spool 43 causing the pressure fluid on each side of piston 24 to become equalized, thereby stopping the latter's movement, and still permitting the above-referred-to free circulation of the fluid through the system.

Leftward movement of valve 26 closes port 40 by spool 42, while exhaust port 41 remains open to port 47, whereupon piston 24 moves leftwardly until port 40 passes beyond spool 42, thereby causing the fluid pressure on each side of piston 75

24 to become equal. It is evident, therefore, that any slight movement in either direction of valve 26 causes a proportional movement of the piston 24 in the same direction and with it, handle 11. The force required to move valve 26 is negligible compared with the force required to move the clutch-shifting handle of the reversing gear, which great force is overcome by hydraulic pressure in response to the movement of valve 26 requiring relatively little force. Furthermore, it is evident that the servo-motor mechanism of this invention is unique in that upon its completion of every operation in response to movement of the valve 26, the fluid in the system continues to circulate without overloading the pump 28, without building up excessive pressures in the system, and most of all, without consuming power from the motor P or S that drives the pump 28. It is pertinent to note also that the valve 31 is simply a relief valve and in the present invention normally does not function, although it would be required to function if the fluid in the circuit were prevented from freely and continuously flowing when the servo-motor was idle.

The valves 26 for each motor P and S are connected to separate draw bars 51 and 52 (Fig. 1) through pivotal joints 51' (only one being shown) for a purpose to be described later. The bars 51, 52 are also provided with pivot mountings 53, 54 that support upstanding bars 55, 56. The bars 55, 56 are pivoted to a stationary shaft 57 located between the ends of bars 55, 56 and shown in Figure 1 as substantially midway of the length of bars 55, 56. From the foregoing, it is evident that the lower ends of bars 55 and 56 move in an arc of a circle, while valves 26 move along a straight line. This angularity is accommodated by the pivotal connections 51' between valves 26 and bars 51, 52. The length of shaft 57, and consequently the distance between bars 55, 56, is such that an operator standing between said bars can conveniently grasp one of the bars 55 and 56 in each hand for simultaneous actuation. Preferably, these bars 55, 56 are located on each side of the steering wheel of the boat. The bars 55, 56 are provided at their upper ends with bosses 58, 59 that support oscillatable hand grips 60, 61. From the foregoing, it is clear that an operator may conveniently grasp hand grip 61 in his left hand and grip 60 in his right hand. Selective oscillation of bars 55, 56 about shaft 57 causes selective operation of the servo-motors S' and, accordingly, selective operation of the reversing-gear mechanisms R.

Conventional carburetors 62, only one of which is shown in Figure 1, are provided for motors P and S and have their butterfly valves actuated separately by draw rods 63, 64. The rods 63, 64 are connected through ball and socket joints 65, 66 to horizontally-disposed links 67, 68. The opposite ends of links 67, 68 are rigidly attached to vertically-disposed rods 71, 72 forming bell-crank levers therewith. The rods 71, 72 pass through fixed guide members 73, 74, 75, 76. The upper ends of rods 71, 72 are rigidly attached to links 77 and 78, respectively, forming bell-crank levers therewith. The links 77, 78 are also provided with additional ball and socket joints connecting them to horizontally-disposed rods 79 and 80 that are located in the horizontal plane containing the longitudinal axis of shaft 57. Shafts 79 and 80 are connected to links 81, 82 through ball and socket joints and these links are rigidly connected to rods 83, 84 forming bell-crank levers therewith. The rods 83, 84 extend

from the longitudinal axis of shaft 57 upwardly along bars 55, 56, respectively, and are connected to hand grips 60, 61, respectively.

The construction and arrangement of the parts are such that oscillation of hand grips 60, 61 about their longitudinal axes causes oscillation of rods 83, 84; links 81, 82; rods 79, 80; links 77, 78; rods 71, 72; and links 67, 68. Oscillation of links 67, 68 causes reciprocation of bars 63, 64, thereby actuating the butterfly valves of the carburetors for engines P and S. The location of links 81 and 82 in a horizontal plane including the longitudinal axis of shaft 57 permits oscillation of bars 55, 56 about said axis without disturbing the linkage for the carburetor control.

From the foregoing description it is evident that the carburetors 62 of the engines P and S should not be accelerated during the operation of the reversing-gear mechanisms R; otherwise the latter will prematurely fail due to the excessive wearing of the clutch plates thereof. Referring to Figures 4 and 5, the handle 61 is provided with a cylindrical portion 85 having diametrically-opposite machined slots 86, 87 forming a section 88 of substantially rectangular outline. The section 88 is adapted to cooperate with a frame 89 having three portions 90, 91 and 92 which permit the unrestricted oscillation of the handle 61 so that the motor S can be accelerated at will when handle 61 is in position so that the section 88 thereof cooperates with said portions 90, 91 and 92. The portion 90 corresponds to the reversing gear R being in position to cause forward motion of the boat; portion 91 is neutral; and portion 92 corresponds to the reversing gear being in position to effect reverse motion of the boat.

A narrow passage 93 joins portions 90 and 91, while a similar passage 94 joins portions 92 and 91. The passages 93 and 94 are of such construction that handle 61 will be forced into a predetermined oscillatable position (idling speed for the engine) before the rectangular section 88 can pass therethrough. This action is caused by cams 90', 91'; 91'' and 92' which, while shown integral with the frame 89, may be separate, adjustable cams affixed thereto. Accordingly, the frame 89 and construction of the handle 61 prevent the operation of the carburetor 62 while the reversing-gear mechanism R is being operated. An identical mechanism is provided for the handle 60.

Referring to Figure 3, a quadrant 95 is keyed to handle 61 having ratchet teeth 96 thereon which cooperate with a stationarily-located spring-pressed detent 97 for retaining the handle 61 in any adjusted position.

Referring to Figure 2, a modified form of the combined reversing-gear and throttle operator is shown. In this embodiment, an oscillatable handle 61' is pivoted to a shaft 57' adjacent to said handle; whereas in Figure 1, the shaft 57 is at a substantial distance from its handle 61. The handle 61' is connected to a rod or flexible shaft 98 through a universal joint 99, the pivotal axes of which lie substantially in the same horizontal plane including the axis for shaft 57'. The flexible shaft is connected to the carburetor, and the servo-motor S' is connected through any desired linkage to an arm 100 integral with the support for the handle 61'.

Although the principles of the invention have been shown and described in detail to fully illustrate several embodiments of the invention, it is obvious that numerous changes may be made in the linkage and such details, and certain fea-

tures may be used without others without departing from the principles of the invention. For example, the servo-motors may be omitted and the reversing mechanism mechanically operated, as would be desirable, particularly from a cost standpoint, in stock-built craft.

What is claimed is:

1. In a boat, propelling mechanism; an internal combustion engine drivingly connected to 10 said propelling mechanism; a throttle mounted on said engine; a reversing gear within the driving connection between said engine and propelling mechanism having an operating lever connected thereto for rendering said gear effective and ineffective; a supporting shaft adapted to be attached to the frame of said boat; a lever pivotally connected to said supporting shaft; a draw bar connected between one end of said pivoted lever and said operating lever; a handle connected to the other end of said pivoted lever in a manner so that it can be oscillated about its own longitudinal axis; means connecting said handle to said throttle, said means being responsive to the oscillation of said handle to control said throttle; and a support stationarily mounted relatively to said supporting shaft and including means for cooperating with means integral with said handle for preventing the oscillation of said handle while said pivoted lever is being moved between different pivotal positions.
2. In a boat having a steering wheel, a port motor and a starboard motor; a reversing gear connected to each motor; propelling mechanism connected to each reversing gear; a reversing-gear arm connected to each reversing gear; a throttle attached to each motor; means for maneuvering said boat independently of said steering wheel comprising a supporting member stationarily mounted in close proximity to said steering wheel; operating levers pivotally mounted on said supporting member in spaced relation such that each may be grasped by one hand of an operator simultaneously; a draw bar connected between one end of each of said levers and the reversing-gear operating arm of its respective motor; a handle connected to the other end of each of said operating levers in a manner so that it can be oscillated about its own longitudinal axis; and means connecting said handle to said throttle, said means being responsive to the oscillation of said handle to control said throttle.
3. In a boat having a steering wheel, a port motor and a starboard motor; a reversing gear connected to each motor; propelling mechanism connected to each reversing gear; a reversing-gear arm connected to each reversing gear; a throttle attached to each motor; means for maneuvering said boat independently of said steering wheel comprising a supporting member stationarily mounted in close proximity to said steering wheel; operating levers pivotally mounted on said supporting member in spaced relation such that each may be grasped by one hand of an operator simultaneously; a draw bar connected between one end of each of said levers and the reversing-gear operating arm of its respective motor; a handle connected to the other end of each of said operating levers in a manner so that it can be oscillated about its own longitudinal axis; and means connecting said handle to said throttle, said means being responsive to the oscillation of said handle to control said throttle; and a plate for each of said handles stationarily mounted relatively to said supporting member and in cooperating position relatively to its

handle, each of said plates being provided with cam means for cooperation with its handle to force said handle into an oscillatable position for idling its respective motor when its corresponding operating lever is pivotally moved in a manner to operate its corresponding reversing gear.

4. In a boat, an internal combustion engine; a throttle mounted on said engine; propelling mechanism for said boat connected to said engine; a reversing gear connected between said engine and said propelling mechanism; an operating arm connected to said reversing gear; a stationarily-mounted bracket; a lever pivotally mounted on said bracket; a servo-motor between said reversing gear and said lever; a draw bar having its one end connected to one end of said pivoted lever and its other end connected to said servo-motor; an oscillatable handle connected to the other end of said pivoted lever; a bell crank connected to said pivoted lever and adapted to be operated within a plane including the axis of the bracket about which said lever pivots and said plane being at substantially right angles to said lever; and means connecting said bell crank with said handle and said throttle, whereby the oscillation of said handle operates said bell crank and said throttle independently of the movement of said lever about the axis of its pivotal mounting on said bracket.

5. In a boat, an internal combustion engine; a throttle mounted on said engine; propelling mechanism for said boat connected to said engine; a reversing gear connected between said engine and said propelling mechanism; an operating arm connected to said reversing gear; a stationarily-mounted bracket; a lever pivotally mounted on said bracket; a servo-motor between said reversing gear and said lever; a draw bar having its one end connected to one end of said pivoted lever and its other end connected to said servo-motor; an oscillatable handle connected to the other end of said pivoted lever; a bell crank connected to said pivoted lever and adapted to be operated within a plane including the axis of the bracket about which said lever pivots and said plane being at substantially right angles to said lever; means connecting said bell crank with said handle and said throttle, whereby the oscillation of said handle operates said bell crank and said throttle independently of the movement of said lever about the axis of its pivotal mounting on said bracket; and a plate stationarily mounted relatively to said bracket and including means for cooperating with said handle for preventing the oscillation of said handle while said pivoted lever is being moved between different pivotal positions.

6. In a power boat, propelling mechanism; a prime mover connected to, and adapted to operate said propelling mechanism; a throttle connected to said prime mover; a reversing gear operatively connected to said prime mover and said propelling mechanism for changing the direction of rotation of said propelling mechanism; an operating arm connected to said reversing gear; a stationary bracket; a lever pivotally mounted on said bracket; a servo-motor including a cylinder mounted in aligned relation with said arm and

lever; a reciprocable valve connected to the one end of said pivoted lever; a piston within said cylinder connected to said arm, housing said valve and adapted to seek a balanced position each time said valve is reciprocated; valve ports between said piston and valve for providing continuous flow of fluid through said servo-motor when said piston is in its balanced position; an oscillatable handle connected to the end of said pivotally-mounted lever opposite that connected to said valve; and means connecting said oscillatable handle to said throttle and responsive to the oscillation thereof for controlling said throttle.

7. In a boat having a steering wheel, a port motor and a starboard motor; propelling mechanism connected to each reversing gear; a reversing-gear arm connected to each reversing gear; a throttle attached to each motor; means for maneuvering said boat independently of said steering wheel comprising a supporting member stationarily mounted in close proximity to said steering wheel; operating levers pivotally mounted on said supporting member in spaced relation such that each may be grasped by one hand of an operator simultaneously; a servo-motor for each of said motor including a cylinder mounted in aligned relation with the arm and lever of each motor; a reciprocable valve connected to the one end of each of said pivoted levers; a piston within each cylinder connected to its corresponding reversing-gear arm, housing its respective valve and adapted to seek a balanced position each time its valve is reciprocated; valve ports between each piston and its valve for providing continuous flow of fluid through each servo-motor when its piston is in its balanced position; a handle connected to the end of each of said levers opposite that connected to said valves in a manner so that each can be oscillated about its own longitudinal axis; and means connecting said handles to its corresponding throttle, said means being responsive to the oscillation of its handle to control the corresponding throttle.
